I claim the ornamental design for a front suspension assembly for a motorcycle, as shown and described.

DESCRIPTION

Reference is made to a concurrently filed Utility application Ser. No. 13/135,298 entitled Suspension System for Steerable Front Wheel of Vehicle, the disclosure of which is incorporated herein by reference.

FIG. 1 is a perspective view of my design from the left side and bottom thereof;

FIG. 2 is a perspective view from the right side and bottom thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines at the top of the tubes in FIGS. 1, 2, 3, 4, 5 and the outermost lines at the top of the tubes in FIG. 6 are boundary lines, while the other broken lines illustrate environmental structure. None of the broken lines form part of the claimed design.
